UNITED STATES PATENT OFFICE

105,234

DESIGN FOR A COMBINED RADIO CABINET AND LAMP

George A. Stamm, Lincoln Township, Berrien
County, Mich.

Application October 17, 1936, Serial No. 65,334

Term of patent 3½ years

To all whom it may concern:

Be it known that I, George A. Stamm, a citizen of the United States, residing in Lincoln Township, in the county of Berrien, State of Michigan, have invented a new, original, and ornamental Design for a Combined Radio Cabinet and Lamp, of which the following is a specification, reference being had to the accompanying drawing forming a part thereof.

Figure 1 is a view of a combined radio cabinet and lamp in front elevation, showing my new design;

Figure 2 is a side view thereof; and
Figure 3 is a perspective view.

I claim:

The ornamental design for a combined radio cabinet and lamp as shown.

GEORGE A. STAMM.
